UNITED STATES PATENT OFFICE

JAMES H. RAND, JR., OF BUFFALO, NEW YORK, ASSIGNOR TO REMINGTON TYPEWRITER COMPANY, OF ILION, NEW YORK, A CORPORATION OF NEW YORK

TYPEWRITING MACHINE

Application filed January 13, 1932. Serial No. 586,348.

My invention relates to typewriting machines and is directed to means for converting at will a noiseless machine into a noisy machine, by which means a noiseless machine in 5 its operation may be made to produce a noise such as is produced in the hammer-blow typewriting machine when the types strike the platen.

In the operation of noiseless typewriting machines there is a pronounced psychological effect on some operators, especially those who have previously operated noisy machines. This is due to the fact that in operating a noiseless machine the operator hears no 15 noise, and the "touch" on such machines is usually much lighter than in noisy machines. Therefore, the operator has the mental attitude that she is not writing or obtaining any result from the operation of the keys, or that 20 she is not attaining her usual speed, due almost wholly to the entire absence of the usual clatter to which she is accustomed. It is difficult in some instances to overcome this purely mental attitude, or to convince the operator that she is in fact writing at possibly 25 an even greater speed than she ordinarily attains on a noisy machine, and with the expenditure of less effort.

One of the main objects of my invention is 30 to overcome these difficulties and to provide means whereby a noiseless machine may be readily converted at will into a noisy machine, or one that simulates the noise produced by the hammer-blows of the types in such machines. This is preferably accomplished 35 without in any manner modifying the pressure-imprint or "touch" of the noiseless machine.

I also provide in some instances means 40 whereby the tone-effect or degree of noise produced may be modified, either increased or decreased, at will.

By these means the noiseless machine may 45 be so regulated for the time being as to cause it to give forth the noise an operator having the mental attitude referred to above is used to, and thus to exclude from her mind dissatisfaction she would otherwise have with the machine. By occasionally eliminating 50 noise, or gradually reducing it, the operator

will eventually overcome the mental attitude mentioned above, and as soon as that is overcome she will accept the noiseless feature of the machine with enthusiasm.

The devices of my invention may be employed only in machines used in demonstration of noiseless machines, or all noiseless machines may be equipped with them, since the expense in providing such devices is in- 55 significant. 60

An advantage of the present invention is that the devices thereof are in the nature of attachments that may be readily embodied in noiseless machines without modifying or materially modifying the existing structural 65 features thereof. 65

To the above and other ends which will hereinafter appear my invention consists in the features of construction, arrangements 70 of parts and combinations of devices set forth in the following description and particularly pointed out in the appended claims. 70

In the accompanying drawings wherein like reference characters indicate corresponding parts in the different views: 75

Fig. 1 is a fragmentary, skeletonized, vertical, fore-and-aft sectional view of a sufficient number of parts of one form of a typewriting machine to illustrate my invention in its embodiment therein. 80

Fig. 2 is a detail, fragmentary, sectional view of a part of the same taken on the line 2—2 of Fig. 4 and seen in the direction denoted by the arrows at said line. 85

Fig. 3 is a fragmentary, sectional view of a modified form of construction, the section being taken on the line 3—3 of Fig. 5 and seen in the direction denoted by the arrows at said line. 85

Fig. 4 is a detail, fragmentary, horizontal, 90 sectional view of a portion of the machine illustrated in Fig. 1.

Fig. 5 is a view that corresponds to Fig. 4 but shows a modified form of sounding device and illustrates the invention embodied 95 in a portable machine.

Fig. 6 is a detail, perspective view of the sounding device illustrated in Figs. 3 and 5.

The devices of my invention are shown embodied in the present instance in a noiseless 100

typewriting machine similar to that disclosed in the application of George G. Going, Serial No. 365,885, filed May 25, 1929, (now Patent No. 1,840,503, dated Jan. 12, 1932), and such as the Remington noiseless portable or "No. 7X Remington machine" and "No. 7 Remington machine". While my invention may be readily embodied in such machines without modifying, or materially modifying, the existing structural features thereof, it should be understood that the invention is not restricted in its use to such machines, but may be employed with almost equal facility in other noiseless typewriting machines such for example as the No. 6 Remington noiseless machine.

Referring more particularly to Fig. 1, it will be seen that each type action includes a type bar 10 pivoted at 11 to a type bar segment 12. The heel of each type bar is provided with an engaging projection 13 seated in an opening 14 in actuating link 15. Each link 15 is pivoted at 16 to an angular sub-lever 17 which in turn is pivoted at 18 on a hanger 19 detachably secured to a supporting plate 20. A link 21 connects each angular sub-lever 17 with its companion key lever 22 provided with a finger key 23. The key levers 22 are pivoted on pivot wires 24 and 25, being guided by front and rear guide combs 26 and 27 respectively.

Each type bar is connected to toggle linkage that is set in motion by the associated type bar and controls its movement to slow up the type bar at the last part of its printing stroke and produce a noiseless pressure-imprint as distinguished from a hammer-blow produced by a type bar in a noisy machine.

Thus, there is pivoted to each type bar at 28 a toggle link 29 which in turn is pivoted at 30 to its companion toggle link 31. The toggle links 31 are anchored at 32, to a fixed part 33 of the frame. Each link 31 has a laterally extending projection 34 to which there is pivoted at 35 a link or member 36 of a second toggle. A weighted member or momentum accumulator 37 is connected to or forms part of each link 36 and exerts its force to straighten the toggle 29, 31. Each link 36 is pivoted at 38 to its companion toggle link 39 which is pivoted at 40 to the type bar segment. A contractile returning spring 41 for each type action is connected at one end to its companion link 15 and is anchored at the other end to the associated hanger 19. The force of each spring 41 is exerted to return all parts of the associated type action to normal position. Each link 39 is provided with a projection 42 that coacts with a buffer plate 43 carried by the segment 12, the companion projection 42 reaching the buffer plate at or about the instant that the type on the actuated type bar reaches the platen 44 and effects a noiseless pressure-imprint thereon, or on the paper carried by the platen.

A universal bar 45 is actuated by each type bar to control the escapement mechanism, whereas a second universal bar 46 underlies all of the key levers 22 and is actuated thereby. The second universal bar 46 is carried by arms 47 fixed to a rock shaft 48 pivoted at its ends on pivot screws threaded into the side plates 49 of the machine frame. The universal bar 46 is employed in this machine to actuate the ribbon vibrator and ribbon feed mechanism, not shown, but which are disclosed in the application of George G. Going, Ser. No. 363,757, filed May 17, 1929. Thus, an upright arm 50 is fixed to the rock shaft 48 and is pivoted at 51 to a link 52 by which the ribbon feed mechanism (not shown) is actuated. A similar arm 53 is fixed to the rock shaft 48 and is pivoted to a second link 54 by which the ribbon vibrator (not shown) is actuated. A contractile return spring 55 is connected at one end to the arm 53 and is anchored at its other end to a plate 56. This spring returns the rock shaft 48 and the parts connected therewith to normal position when a depressed printing key is released by the operator and returns to normal position.

Since this second universal bar 46 is actuated at each operation of a type action and is conveniently located for the purpose I avail myself of it to actuate the sounding device of my present invention at each printing operation. It should be understood, however, that any suitable part of the machine that is actuated at each printing operation may be employed to operate the sounding device. In the present instance I detachably affix an arm 57 to the universal bar 46 by screws 58. The lower free end of the arm 57 carries a hammer-head 59 that is adapted to strike a sounding device or sounding board 60 (when the latter is in the path thereof) at each actuation of a printing key 23, and thus produce a noise that simulates the hammer blow of an ordinary type bar against the platen. From an inspection of Fig. 1 it will be seen that a depression of any printing key is effective to move the universal bar 46 down to the full from the dotted line position shown in this view. A corresponding movement is transmitted to the arm 57 and the hammer-head 59, causing the latter to impact with the sounding device 60 at about the same instant that the type is impressed against the platen, thereby simulating the sound that is ordinarily produced in the hammer-blow machine by the types striking the platen.

In the construction shown in Figs. 1 to 4 inclusive the sounding board 60 is made of wood and is fixed by screws 61 to a supporting arm 62. In this "No. 7 Remington" construction the machine is not fixed on a base board, as is the case in the portable machine or "No. 7X Remington machine" shown in

Figs. 3, 5 and 6, but is supported on feet 63 like the usual standard office machine. A pair of the feet 63 on each side of the machine is attached in the present instance to a strip 64 of resilient metal, and each strip 64 is attached by headed screws 65 to the frame of the machine. Thus, the stem of each screw 65 passes through the associated strip 64 and an intermediate washer 66 and then takes into a tapped opening in a bracket 67 secured to a side plate 49 of the machine. This spring supported mounting for the machine was not invented by me. In this form of the construction I prefer to pivot the supporting arm 62, as indicated, by screw bolt 68, on one of the resilient strips 64. A spring friction washer 68^a is interposed between the arm 62 and head of the bolt to hold the arm 62 in the position to which it may be adjusted around its pivot 68. The arm 62 extends beyond one side of the machine (and the outer shell 69 thereof) where the arm is provided with a finger piece 70. With the aid of this finger piece the arm may be moved from the full to the dotted line position shown in Fig. 4, and vice versa, thus moving at will the sounding device or board 60 into and out of the path of the hammer 59, thereby rendering the sounding device effective or ineffective at will.

In Figs. 3, 5 and 6 I have shown a modified form of construction in which a metal arm or sounding device 71 is apertured at 71^a to receive a wood screw 72 threaded into the base board 73 to which the machine is attached in the usual manner. A spring friction washer 72^a is interposed between the member 71 and the base board to hold said member against accidental displacement from any position to which it may be adjusted around its pivot. The arm or member 71 extends beyond one side of the machine and terminates in a finger piece 74 by which said device may be shifted or adjusted at will to any of the three positions indicated in Fig. 5. A second metal arm 75 of considerably less thickness than the arm 71 is fixedly secured to the latter by spot welding, or in any other suitable manner, to radiate from the pivotal center thereof. It will be understood from a consideration of Fig. 5 that when the operator adjusts the member 71, 75 to the full line position, the inner end of the arm 71 will be brought into the path of the hammer-head 59 and will give forth one tone or character of noise at each actuation of a printing key; such noise closely simulating the hammer-blow of a type bar in an ordinary noisy machine. When, however, the finger piece 74 is shifted to the left from the full line position, shown in this figure, the thinner arm 75 will be brought into the path of the hammer 59, thereby giving forth a different tone or decidedly reduced extent of noise at each printing operation, but

nevertheless simulating the hammer-blow of a type bar in a noisy machine. When the finger piece 74 is moved to the right-hand position shown in Fig. 5, both arms 71 and 75 will be carried out of the path of the hammer-head 59, thereby rendering the sounding device ineffective and the machine noiseless.

While I have described in detail two forms of sounding devices, it should be understood that within the broad aspects of my invention any suitable sounding means of the general character indicated, and for the purposes specified, may be employed in any character of noiseless machine to be rendered operative or inoperative at will. It will be understood, therefore, that various changes may be made in the construction, and parts thereof may be employed without others, without departing from any invention as it is defined in the accompanying claims.

What I claim as new and desire to secure by Letters Patent is:

1. In a noiseless typewriting machine, the combination of a type-action including means for effecting substantially a noiseless pressure-imprint, noise-producing means operating at each actuation of said type-action for simulating the noise produced in a hammer-blow typewriting machine, and means for at will rendering said noise producing means effective or ineffective.

2. In a noiseless typewriting machine, the combination of a type-action including means for effecting substantially a noiseless pressure-imprint, noise-producing means operating at each actuation of said type-action for simulating the noise produced in a hammer-blow typewriting machine, and means for at will rendering said noise-producing means effective or ineffective without in any manner modifying the operation and printing effect of said type action.

3. In a noiseless typewriting machine, the combination of a plurality of type-actions each including means for effecting substantially a noiseless pressure-imprint, an actuating member operated at each actuation of any of said type-actions, a hammer controlled by said actuating member, a sounding device with which said hammer coacts, and means operable at will for rendering said hammer effective or ineffective on said sounding device.

4. In a noiseless typewriting machine, the combination of a type-action including means for effecting substantially a noiseless pressure-imprint, noise-producing means operating at each actuation of said type-action for simulating the noise produced in a hammer-blow typewriting machine, said noise-producing means including means by which the tone or degree of noise may be varied without modifying the operation of the type-action, and means for at will rendering said

noise-producing means effective or ineffective and for at will modifying the tone or degree of noise produced.

5. In a noiseless typewriting machine, the combination of a plurality of type-actions each including means for effecting substantially a noiseless pressure-imprint, an actuating member operated at each actuation of any of said type-actions, a hammer controlled by said actuating member, a sounding device with which said hammer coacts, and hand controlled means operable at will for moving said sounding device into and out of the path of said hammer and for maintaining the sounding device indefinitely in either of such positions.

6. In a noiseless typewriting machine, the combination of a plurality of type-actions each including means for effecting substantially a noiseless pressure-imprint, an actuating member operated at each actuation of any of said type-actions, a hammer controlled by said actuating member, a sounding device with which said hammer coacts, said sounding device having means for giving forth different tones or degrees of noise from the blow of the hammer depending on the position of said device relatively to the hammer, and hand-controlled means operable at will for shifting said sounding device relatively to said hammer and for maintaining it indefinitely in any of said shifted positions, whereby the sounding device may be adjusted to afford different sounds or degrees of noise or may be thrown out of the path of the hammer and rendered inoperative.

7. In a noiseless typewriting machine, the combination of a plurality of type-actions each including means for effecting substantially a noiseless pressure-imprint, a hammer actuated at each operation of any of said type-actions, and a sounding board mounted for movement into and out of the path of said hammer.

45 8. In a noiseless typewriting machine, the combination of a plurality of type-actions each including means for effecting substantially a noiseless pressure-imprint, a hammer actuated at each operation of any of said type-actions, and a sounding device having different portions thereof of different thicknesses to produce different tones or degrees of noise when struck by said hammer, and means for mounting said sounding device for shifting movement to bring either of said different portions thereof into the path of the hammer or to move said sounding device out of the path of said hammer.

60 9. In a noiseless typewriting machine, the combination of a plurality of type-actions each including a key-lever, and means controlled thereby for effecting substantially a noiseless pressure imprint, a universal bar actuated by said key-levers, a hammer carried by said universal bar, a sounding device

with which said hammer coacts, and means for shifting said sounding device into and out of the path of said hammer.

10. In a noiseless typewriting machine, the combination of a plurality of type-actions each including a key-lever, and means controlled thereby for effecting substantially a noiseless pressure-imprint, a universal bar actuated by said key-levers, a hammer carried by said universal bar, a sounding device constructed to give forth different tones or degrees of noise depending on its effective position relatively to said hammer, and hand-controlled means for adjusting said sounding device relatively to said hammer to vary the effective position of said device and adjust it into and out of the path of said hammer.

Signed at Buffalo in the county of Erie and State of New York this 7th day of January, 85 A. D. 1932.
